UNITED STATES PATENT OFFICE.

WILLIAM BOWMAN AND ERNEST HUNSCHER, OF CLEVELAND, OHIO.

CARPET-CLEANING APPARATUS.

SPECIFICATION forming part of Letters Patent No. 271,406, dated January 30, 1883.

Application filed May 23, 1882. (No model.)

To all whom it may concern:

Be it known that we, WILLIAM BOWMAN and ERNEST HUNSCHER, both of Cleveland, in the county of Cuyahoga and State of Ohio, 5 have invented a new and Improved Apparatus for Cleaning Carpets, of which the following is a full, clear, and exact description.

This invention relates to improvements in that class of carpet-cleaners, in which the cleaning is done by the tumbling and rubbing process; and it consists in the combination and arrangement of parts, substantially as herein-after more fully set forth.

We construct a tower of suitable height and 15 provide an endless carrier for elevating the carpets, and also friction or tumbling frames, over which the carpets roll in their descent, as hereinafter described and claimed.

Reference is to be had to the accompanying 20 drawing, in which our carpet-cleaning apparatus is shown by a perspective elevation.

A A is the frame-work of the tower, which is to be of any suitable height. At the lower part of the tower are cross-shafts *a a*, fitted in 25 suitable bearings and provided with pulleys *b*, and at the upper part of the tower are similar shafts and pulleys *a b*.

Around the pulleys *b b* is fitted an endless apron, B, composed of belts *c*, to which slats 30 *d* are attached.

Within the frame-work of the tower are the breakers or friction-frames D, which are placed at suitable distances apart and inclined in opposite directions alternately. These frames 35 D are provided with rollers *e* and slats to form a surface over which the carpets roll, and the frames are pivoted at one end and connected at their outer ends to a center bar, *f*, by a screw and nut, as shown at *g*, so that their inclination may be varied, the object being to 40 regulate the speed at which the carpets move over the frames, less inclination being required with heavy carpets than with lighter ones.

The endless apron is provided at intervals with shelves, pockets, or carriers *h*, which are 45 attached to the inner side of the apron for elevating the rolls of carpet.

In operation, power is to be applied to one of the shafts *a* to give a movement to the endless apron. The rolls of carpeting are placed 50 upon the apron between the lower pulleys, and are carried upward by the shelves *h* until they reach the upper end of the tower, when they roll over upon the frame D, and are passed from thence to the next frame, and so on 55 downward until they reach the bottom. By this movement the carpets are turned end for end and rolled and tumbled about so that, practically, they clean themselves and no one carpet comes in contact with another. 60

The operation being in the open air, and the tower open at all sides the dust and dirt are carried away. By making the tower of suitable height and strength and giving to the belt the necessary speed the apparatus 65 can be made to do the work rapidly, and the cleaning will be effectively done at a much less expense than by the ordinary beating operation.

Having thus described our invention, we 70 claim as new and desire to secure by Letters Patent—

1. The carpet-cleaning apparatus consisting of the tower A, the endless apron B, provided with carriers *h*, and the series of inclined friction-frames or breakers D, substantially as 75 described, combined for operation as set forth.

2. In carpet-cleaning apparatus, the adjustable frames D, provided with rollers *e*, in combination with the elevating belt or apron B, 80 substantially as shown and described.

WILLIAM BOWMAN.
ERNEST HUNSCHER.
